UNITED STATES PATENT OFFICE.

JOSEPH E. CAMP, OF WASHINGTON, ILLINOIS, ASSIGNOR TO CAMP BROS. & CO., OF METAMORA, ILLINOIS, A CORPORATION OF ILLINOIS.

GRAIN-DUMP.

No. 890,022.

Specification of Letters Patent.

Patented June 9, 1908.

Application filed June 15, 1905. Serial No. 265,301.

To all whom it may concern:

Be it known that I, JOSEPH E. CAMP, citizen of the United States, residing at Washington, in the county of Tazewell and State of Illinois, have invented certain new and useful Improvements in Grain-Dumps; and I do hereby declare that the following is a full, clear, and exact description of the invention, which will enable others skilled in the art to which it appertains to make and use the same.

This invention has reference to a portable hydraulic grain dump.

The primary object of my invention is to combine with a device for supporting and carrying the front wheels of a wagon, a hydraulic mechanism by which the wagon may be readily elevated.

A further object is to combine certain means with hydraulic pumping mechanism by which the wagon in its various movements can be controlled while the pumping mechanism is in continual operation.

A further object is to combine with hydraulic pumping mechanism certain means whereby the raising and lowering of the wagon can be readily governed.

Another object is to provide a hydraulic power for a wagon dump, and combine therewith means by which the movement of the wagon can be both manually and automatically controlled, all of which will appear.

In the drawings appended, Figure 1 is a side elevation of my improved grain dump. Fig. 1^a is a detail of a valve operating mechanism. Fig. 2 is an end elevation of the dump. Fig. 3 is a perspective view of a portion of the grain dump showing its platform partly raised. Fig. 4 is a top view of a portion of the grain dump showing piping for connecting the pump which elevates the platform. Fig. 5 is a perspective view of the upper end of a piston-rod and cross-head used for raising the platform. Fig. 6 is a side elevation of a pump used for the raising operation of the platform.

To my knowledge wagon dumps have not heretofore been provided with hydraulic means for raising the wagon. I am aware that some such arrangement has been used on devices for loading ships with grain and coal from railway cars, however, but the apparatus is very different from that which I am about to describe. The apparatus referred to has, in fact, no details as to the

pumping arrangement, and it is designed for local use only and cannot be transported after the manner of a wagon dump for obvious reasons. Furthermore, the fluid supply for the mechanism, which must be large, is of necessity a local or stationary one whereas, I provide a receptacle for the fluid which is portable with the operating mechanism and with the dump proper.

A is the body of the grain dump suitably mounted near one end on wheels B and having at the other end a tongue C by which the apparatus can be transported, though of course, I do not confine myself to the particular way of mounting it. Erected on said body is a derrick in the form of an A, indicated by the letter D there being one of said derricks at each side of the body as shown in Fig. 2. The derrick shown in Fig. 1 comprises two parallel members a, b supported by a single member c as shown, there being a space d between said members a, b for the purposes shown hereinafter. Lying across the said body A and let flush therewith is a member E, Fig. 3, of any desired form, which in said figure is shown slightly raised above the body with a portion of a wheel resting thereon to illustrate its use. Secured at each end of the member E is a frame F each having a series of three flanged rollers, two of which lie within the space d between the members a, b and the corresponding two of the opposite frame F resting upon its adjacent derrick D as in Fig. 2. The third roller of each said frame, as shown in Figs. 1 and 3, lies behind and against the same derrick member as do the two companion rollers as will be fully understood.

In Fig. 3 it will be noted that the two derricks D described differ in that the one at the left of the figure is composed of two parallel members, while the one at the right is composed of but a single one supported by a member arising from an opposite angle.

In Figs. 1 and 3 a cylinder G is shown forward of and lying against the derrick D and secured thereto in any good manner and having the usual piston-rod and piston H and J respectively, indicated in dotted lines. Secured to opposite sides of the derrick member a, against which the cylinder rests, are guide rods K for a cross-head L carried at the end of the piston-rod, said cross-head being notched to straddle the rods as shown in Fig. 5. One end of the cross-head L car-

ries an arm M whose free end carries a rod N parallel with the piston-rod, said rod N having connection with the frame F below it and which is secured to the member E as already described. At the other end of the cross-head is an eye O to which is attached one end of a cable P which passes downward at the outside of the derrick between two pulleys Q on the latter and under a pulley R in the body A. From thence the rope or cable passes under the floor of said body (see dotted lines Fig. 2) and under a pulley S, thence up at the side of the derrick over a pulley T and down inside the derrick where its end is attached to frame F of the member E.

U represents the conveyer extending across the body A which is usually employed for receiving the grain from the wagon, and V indicates the elevator for raising the grain into bins or other receptacles. The details of these two members have not been shown, however, since they form no part of the invention in issue. But the elevator shaft is shown at W one end of which is carried in a bearing X removed some distance from said elevator, said shaft being driven by means of a belt Y and pulley Z. On the shaft between the pulley and the said bearing X is an eccentric 3 having an eccentric strap 2 forming part of a piston and piston-rod 4, Fig. 6. Mounted on the side of the body A is a cylinder 5 by means of members 6 which allow a slight pivotal movement, and within said cylinder the piston 4 is designed to have vertical movement by means of the said eccentric. At 7 is a tank for containing oil or water and into this tank is connected a pipe 8 also connected into the bottom of the cylinder 5 described, the latter as will be seen, constituting a pump. A pipe 9 is connected into the bottom of the cylinder G of the derrick D and also into the cylinder or pump 5 as shown. Another pipe connects the pipe 9 with the tank 7 as indicated by 10 the purpose of which will now be described.

In operation a loaded wagon is driven upon the platform or body A so as to place its front wheels upon the member E, its rear end overhanging the conveyer U as is common practice. The elevator being in operation by being driven from the belt Y described, imparts a reciprocating movement to the piston 4 of the pump 5 to draw oil from the tank 7 and force it into the pipe 9, this being possible by the placing of a check-valve 11 in the pipe 8 and one in said pipe 9 indicated at 12 said valves being constructed and arranged whereby oil may pass through the pipe 8 from the tank 7 to the pump but cannot return therethrough and so that oil can be forced into the pipe 9 toward the cylinder G but cannot return to the pump. The continuous operation of the pump, therefore, transfers the oil from the tank 7 to the cylinder G thereby causing the piston J of the

latter to be elevated with the result that the member E is raised on the derricks by means of the rod N on the cross-head L and the cable P, it being seen that said cable imparts a raising movement to the platform corresponding to that given by said rod N. This elevates the front end of the wagon so as to dump the load into the conveyer U. When the cross-head reaches a point near the end of its upward travel it meets a lever 13 pivoted on the derrick D which has connection by a rod 14 with a cut-off valve 15 in the pipe 8. The said lever is raised to move said valve 15 to stop the flow of oil to the pump 5 and the latter, though running continuously, in being deprived of oil can raise the member E no higher and said member must remain at rest until the operator is ready to lower the wagon after it has been completely unloaded. To accomplish the lowering movement he grasps a lever 16 pivoted near the elevator and by pushing it toward the derrick opens a valve 17 in the pipe 10. Now since the weight of the member E and the wagon are upon the oil in the cylinder G that fluid is under pressure but it cannot return to the pump 5 by reason of the check-valve 12 before mentioned. However, when the valve 17 is opened by the lever 16 the oil is free to return to the tank 7 from which it came. The wagon is thus allowed to fall to its normal position and can then be removed from the platform and having reached this normal position the lever is released and a spring 16^a connected thereto returns it to its first position thereby closing the valve 17; the valve 15 the while, remaining closed until a loaded wagon is again placed in position for dumping at which time the operator grasps a second lever 18 adjacent to the lever 16 which has connection with the rod 14 and by a movement thereof raises said rod to open the valve 15. The oil is then immediately drawn into the pump 5 and the member E is again started upward.

Fig. 1^a shows the connection for the movement of the valve 15 by the lever 18. A rod 19 (see also Fig. 1) connects the said lever with a bell-crank lever 20 pivoted on the derrick D the said lever 20 being slotted at 21 for receiving a pin 22 in the rod 14. It will be seen that a movement of the rod caused by the cross-head will raise the bell-crank lever and also the lever 18 will be shifted on its pivot, while a movement of the lever 18 by hand will move said rod as well as the valve 15. It is at once evident that the valve 17 can be opened just enough to permit the wagon to lower very slowly or by a full opening it may be lowered much faster than it was raised by the pump thus giving the operator perfect control over it. In Figs. 1 and 4 the system of piping and the valves are clearly illustrated but in the other figures these parts have been eliminated in order

that those figures may be more easily read and understood. The pump 5 is allowed a slight pivotal movement to permit the piston to move with the eccentric there being sufficient length of the pipes to permit them to swing with the cylinder, though there are other methods that could be provided as well as this for permitting free movement of the pump since I do not confine myself to this structure and, in fact, it is not my purpose to hold myself to the exact construction shown in the drawings as to any of the parts as many changes may be made that will still be within the meaning of the invention and its claims. The piston J can, of course, be made to operate in the reverse order from that described by pumping the fluid into the top of the cylinder instead of the bottom and this would require the rearrangement of the cable and pulleys.

It is to be observed that the wagon is raised slowly for the reason that the amount of fluid pumped at each stroke is quite small as compared with the capacity of the cylinder G, and further it will be seen that in opening the valve 17 fully the oil can return quickly to the tank 7 thereby lowering the wagon much more quickly than it is raised. As a matter of fact, the wagon should preferably rise slowly so that its contents will not pass out too rapidly otherwise the conveyer would become overloaded. When unloaded the wagon is to be gotten out of the way as soon as possible and this is done by allowing the oil to escape into the tank 7 at once. The latter member may be made of any form and size and placed anywhere out of the way of the wagon. The guides KK on the derrick D serve to keep the piston-rod H in line with its cylinder G and also relieves the strain occasioned by the pull of the cable and the rod N on the cross-head.

Any other form of the member E may be used in preference to that described and shown or any other means can be employed by which to raise the wagon through my hydraulic lifting means. As herein-before stated I do not confine myself to the use of the wheeled platform A, necessarily, since any portable member may be used by which the various necessary parts can be transported.

It is to be observed that the derricks D in being slanted or inclined cause the wagon to be raised in such a way that its rear end is shifted but little where it overhangs the conveyer so that there can be no danger of spilling grain outside said conveyer. If the member E were moved vertically the spilling of grain would result since the wagon in raising would be made to advance and recede according to whether it is raised or lowered and its delivery end would shift to such an extent that the grain would be lost. This may be better understood when it is stated that the line of movement of the member E

will be parallel to a line extending from the center of the front axle when at its lowest position, to the same point at the raised position. In other words, supposing the wagon to be tilted upward using the rear axle as a pivot the front axle will describe a path in the arc of a circle. Now a line drawn through the lowest and highest point reached by the said front axle will be parallel to the angle at which the derricks are placed. Moved thus the delivery end of the wagon would have a very slight movement indeed or one such as to cause no trouble of the kind mentioned.

With regard to the pump it is evident that this member may be arranged to be stopped, if desired, when the wagon has been raised to the desired height for dumping instead of cutting off the fluid supply and thereby accomplish the same object as when stopping said fluid supply through the valve 15. Evidently the valve 15 need not be closed when the piston J is at rest in the raised position or even when in the act of lowering, and the normally closed valve 17 at the same time can be opened very slightly thereby allowing the fluid to circulate through the pump, the pipes and the container 7 without affecting the said piston J; the pressure through the pump and pipe 9 being equal to the pressure upon the piston due to the weight of the wagon and the member E. While water or oil may be used in the mechanism, oil being preferred for obvious reasons, yet air could likewise be used if desired.

1. In a wagon dump, a portable platform, devices carried by the platform for engaging the front end of a wagon, a liquid pressure cylinder and piston supported by the platform, a pump carried by the platform and arranged to force liquid into said cylinder, a source of liquid supply connected with the pump, means whereby proper movement of the piston lifts said devices, and valve controlled means for discharging liquid from the cylinder.

2. In a portable wagon dump a hydraulic pump and means in connection therewith for raising the front wheels of the wagon, means for automatically interrupting the raising movement, and other means for permitting the wagon and its raising means to lower independent of the pumping means.

3. In a portable wagon dump, a continuously acting hydraulic pump and means in connection therewith for raising the front wheels of the wagon, means for automatically interrupting the raising movement and the means for permitting the wagon to lower independent of the said continuously acting pumping means.

4. In a portable grain dump, lifting means for dumping the wagon, hydraulic means for raising such lifting means, means for arresting the upward movement of the wagon, and other means for permitting the wagon to

lower at a faster speed than that at which it is raised.

5. In a portable grain dump, lifting means for dumping the wagon, means operated by hydraulic pressure for raising such lifting means, means in connection with said pressure means for automatically arresting the upward movement of the wagon, and other means also in connection with the pressure 10 for causing the wagon to be lowered.

6. In a portable wagon dump, lifting means for dumping the wagon, a cylinder, a piston, connections between the piston-rod and the lifting means, a source of fluid supply, a pump for forcing fluid into said cylinder,

der to raise its piston, means for interrupting the upward movement of the wagon at any point by stopping the supply of fluid to the cylinder, automatic means for causing the fluid to be held within the latter, and means 20 for permitting escape of the fluid from said cylinder at the time and for the purposes described.

In testimony whereof I affix my signature, in presence of two witnesses,

JOSEPH E. CAMP.
